NO. 3606

WILLIAM GORMAN.

— ASSEMBLIES —

RUSSELL AND ERWIN MFG CO.

DESIGN

— FOR —

DOOR ESCUTCHEON.

PATENTED
AUG 10 1869

United States Patent Office.

WILLIAM GORMAN, OF NEW BRITAIN, CONNECTICUT, ASSIGNOR TO THE RUSSELL AND ERWIN MANUFACTURING COMPANY, OF SAME PLACE.

Design No. 3,606, dated August 10, 1869.

DESIGN FOR A DOOR-ESCUTCHEON.

The Schedule referred to in these Letters Patent and making part of the same.

To all whom it may concern:

Be it known that I, WILLIAM GORMAN, of New Britain, in the county of Hartford, and State of Connecticut, have originated and designed a new Design for Door-Escutcheon; and I do hereby declare that the following is a full, clear, and exact description thereof, reference being had to the accompanying drawings, making a part of this specification.

This design is appropriate to that variety of door-escutcheons which is made to receive the shank of the knob, as well as furnish a plate for the key-hole.

A depression, A, receives the knob-escutcheon, and

the rim surrounding the same is surmounted by a double scroll, B.

The general character of ornamentation is after the Egyptian style, the ornamental scroll-work and the surrounding edge moulding being in relief.

What I claim as my invention, and desire to secure by Letters Patent, is—

The ornamental design for a door-escutcheon, substantially as described, and shown in the drawings.

Witnesses: WILLIAM GORMAN.

M. J. WOODRUFF,

H. E. RUSSELL, 2d.
